DESIGN FOR A RACK FOR SUPPORTING AN INTERCHANGEABLE RADIO RECEIVER UNIT

Frederick H. Drake and John E. Johanson, Boonton, N. J., assignors to Aircraft Radio Corporation, Boonton, N. J., a corporation of New Jersey

Application August 2, 1940, Serial No. 94,156

Term of patent 14 years

To all whom it may concern:

Be it known that we, Frederick H. Drake and John E. Johanson, citizens of the United States, residing at Boonton, county of Morris, State of New Jersey, have invented a new, original, and ornamental Design for a Rack for Supporting an Interchangeable Radio Receiver Unit, of which the following is a specification, reference being had to the accompanying drawing, forming part thereof, and wherein:

Fig. 1 is a perspective view of a rack for sup-

porting an interchangeable radio receiver unit, showing our new design;

Fig. 2 is a plan view of the same;
Fig. 3 is a side elevational view; and
Fig. 4 is a rear elevational view.

We claim:

The ornamental design for a rack for supporting an interchangeable radio receiver unit, as shown.

FREDERICK H. DRAKE.
JOHN E. JOHANSON.
